CLAIM

The ornamental design for an enclosure for control modules, as shown.

DESCRIPTION

FIG. 1 is a front elevational view of the enclosure for control modules showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top, front, right side perspective view of the enclosure for control modules.
